RECLINING ARTICLE OF FURNITURE

Anton Lorenz, Buffalo, N. Y.

Application October 26, 1946, Serial No. 705,992

16 Claims. (Cl. 155—110)

1

The present invention relates to articles of furniture, and more particularly to a reclining article of furniture, wherein the seat and the back-rest form movable links of a polygonal compound linkage including a sliding pair.

An object of the present invention is to provide a reclining article of furniture of above described type, wherein the movable members of the article of furniture are very well balanced, so that an occupant resting in the article of furniture may bring the movable members of the article of furniture from one position into another position without great effort.

A further object of the present invention is to improve upon reclining articles of furniture as now ordinarily made.

With the above and other objects of the invention in view, the invention consists in the novel construction, arrangement and combination of various devices, elements and parts, as set forth in the claims hereof, certain embodiments of the same being described in the specification and being illustrated in the accompanying drawings forming part of this specification, wherein:

Fig. 1 is a side elevational view of an adjustable reclining chair according to the invention.

Fig. 2 is a side elevational view, partly in section, of an arm-rest and some parts connected therewith of the chair shown in Fig. 1, in an enlarged scale.

Fig. 3 is a sectional view taken on line 3—3 of Fig. 2.

Fig. 4 is a fragmentary side elevational view illustrating the holding device for the leg-rest of the chair shown in Fig. 1, in an enlarged scale.

Fig. 5 is a sectional view taken on line 5—5 of Fig. 4.

Fig. 6 is a side elevational view of a different embodiment of an adjustable reclining chair according to the invention.

Fig. 7 is a side elevational view, partly in section, of the arm-rest and some parts connected therewith of the chair shown in Fig. 6, in an enlarged scale.

Fig. 8 is a sectional view taken on line 8—8 of Fig. 7.

Fig. 9 is a side elevational view of another embodiment of an adjustable reclining chair according to the invention, a portion of the side wall of the support being broken away.

Fig. 10 is a side elevational view, partly in section of the arm-rest and some parts connected therewith of the chair shown in Fig. 9, in an enlarged scale.

2

Fig. 11 is a sectional view taken on line 11—11 of Fig. 10.

Fig. 12 is a sectional view taken on line 12—12 of Fig. 10.

Fig. 13 is a side elevational view of another embodiment of a reclining chair according to the invention, a portion of a side wall of the support being broken away.

Fig. 14 is a side elevational view, partly in section, of the arm-rest and some parts connected therewith of the chair shown in Fig. 9, in an enlarged scale, and

Fig. 15 is a sectional view taken on line 15—15 of Fig. 14.

15 Referring now to Fig. 1, 20 generally indicates a support comprising on each side of the chair a supporting member 22 and a supporting member 24 rigidly connected with each other by screws or the like. The supporting members 22 are connected with each other by a bracing rod 26, and the supporting members 24 are connected with each other by bracing rods 28 and 30.

The lower end portion of a back-rest 32 is pivoted to the support 20 at 34. The rear portion of a seat 36 is pivoted to the support 20 at 38 at a point spaced from the pivotal connection 34 between the back-rest 32 and the support 20. On each side of the chair the lower end portion of a front link 40 is pivoted to the front portion of the seat 36 at 42. The upper end portion of each front link 40 is pivoted at 44 to the front portion of a top link generally indicated by 46. The rear portion of each top link 46 arranged in a level above the plane of the seat 36 is pivoted at 48 to an intermediate point of the back-rest 32.

As best shown in Figs. 2 and 3, an intermediate portion 50 of the top link 46 is hollow. A guiding means or guiding rod 52 arranged within said hollow portion 50 of the top link 46 is secured to the latter by means of screws 54. A slider 56 forming the upper portion of a connecting or guiding link 58 and having bores 60 receiving the guiding rod 52 is slidably engaged with said guiding rod 52. The slider 56 in combination with the guiding rod 52 represent a sliding pair of the link-system of the chair. According to the drawings, the slider 56 is integral with the guiding link 58; if desired, however, the slider and the guiding link could be made of separate pieces of material rigidly connected with each other. The lower end portion of the guiding link 58 passing through and projecting from the slot or aperture 62 of the hollow portion 50 of the top connecting link 55 46 is pivoted to the supporting member 24 of the

support 20 at 64 at a point spaced from the pivotal connection 34 between the back-rest 32 and the support 20 and spaced from the pivotal connection 38 between the seat 36 and the support 20.

The above described concealed arrangement of the guiding rod 52, the slider 56 and the upper portion of the guiding link 58 makes a nice and attractive appearance of the chair.

A bar 66 of wood or other suitable material representing the arm-rest is secured to the top link 46 by screws 68.

As will be readily understood from above, the reclining chair comprises a polygonal compound linkage including the stationary portion of the support 20 between the pivots 34 and 38, the 15 movable back-rest 32, the movable top link 46, the movable front link 40, the movable seat 36, the sliding pair 52, 56 and the movable guiding link 58. When the occupant resting in the chair leans the weight of his body against the back-rest, the back-rest 32 may be brought into a reclined position, for example the extreme reclined position 32', and at the same time the seat 36 connected with the back-rest as described above is 20 lifted into the position 36'.

The sitting position of the movable members of the chair shown in full lines is limited by the bracing member 30 on which the seat 36 comes to a rest. The extreme reclined position of the 30 movable members of the chair shown in dash and dot lines is limited by an abutment of the slider 56 against a stop collar 70 secured to the guiding rod 52 as best shown in Fig. 2.

The movable members of the chair may be held in any convenient position, for example the extreme reclined position shown in dash and dot lines or any other intermediate reclined position by means of a locking device generally indicated by 72 and arranged on the pivot 64 as best shown in Figs. 2 and 3. Said pivot 64 having a head 74 resting against a surface of the supporting member 24 is provided with a square portion 76 inserted into a corresponding square aperture of said supporting member 24. Said square portion 76 prevents the pivot or bolt 64 from rotation when a locking knob 78 is screwed on the threaded end of said bolt 64. A washer 80 is interposed between the guiding link 58 and the supporting member 24. When the locking knob 78 is loosened, the guiding link 58 may freely swing about the pivot 64, so that the movable members of the chair connected with said connecting link 58 in the manner described above may be freely moved from one position into another one. When the locking knob 78 is tightened, the guiding link 58 is firmly held in its position, so that the guiding link 58 and the movable members of the chair connected therewith are locked in their position. Of course, a different type of locking means may be used, if desired.

Furthermore, the chair is provided with spring stops generally indicated by 82 and 84 as best shown in Fig. 2, which are useful for resiliently holding the movable members of the chair in the sitting position and the extreme reclined position when the locking knob 78 of the locking device 72 is loosened. The spring stop 82 comprises a resilient blade 86 mounted on a set collar 88 secured to the guiding rod 52. Said resilient blade 86 carries a renewed stop 90 arranged for engagement with the left-hand portion of the slider 56 when the movable members of the chair are in the sitting position shown in full lines in Fig. 1. The spring stop 84 comprises a spring blade 92 mounted on the set collar 70. Said spring blade

92 carries a renewed stop 94 arranged for engagement with the right-hand portion of the slider 56 when the movable members of the chair are in the extreme reclined position shown in dash and dot lines in Fig. 1. Although the spring stops 82 and 84 are strong enough to hold the movable members of the chair in the sitting position and extreme reclined position when the occupant rests quietly in the chair, the resilient action of the blades 86 and 92 is rather weak, so that the spring stops 82 and 84 may be readily disengaged from the slider 56 by a slight pressure exerted by the occupant of the chair on a member of the link-system, when he wishes to change the position.

As best shown in Figs. 1 and 4, a leg-rest 96 is swingably mounted on the front portion of the seat 36 at 42. A lug 98 or the like mounted on the lower end portion of the front link 40 is in loose contact with said leg-rest 96 preferably held against a lug 98 by means of a spring not shown. A holding rod 101 of a holding device generally indicated by 103 is pivotally connected at 105 with a lug 107 of the leg-rest 96. As best shown in Figs. 4 and 5, said holding rod 101 is 20 slidably engaged with a clip 109 swingably mounted on a bolt 111 immovably connected with a bracket 113 secured to the seat 36. A locking knob 115 is screwed on the threaded end of the bolt 111. When the locking knob 115 is tightened, the clip 109 firmly holds the holding rod 101 and the leg-rest 96 connected therewith in its position. When the locking knob 115 is loosened, the holding rod 101 may slide in the clip 109, so that the leg-rest 96 may freely swing about its pivot 42.

Thus, when the locking knob 115 of the holding device 103 is loosened, the front link 40 may swing the leg-rest 96 through the medium of the lug 98 about the pivot 42, for example into the position 96', when the movable members of the chair are brought into the extreme reclined position.

When the movable members of the chair are held by means of the locking device 72 in a predetermined position, for example the sitting position shown in full lines, and when the locking knob 115 of the holding device 103 is loosened, the leg-rest 96 may be swung by hand into a different position relative to the seat, for example into the position 96'', wherein it may be subsequently locked by a tightening of the locking knob 115 of the holding device 103.

According to the embodiment of an adjustable reclining chair shown in Fig. 6, the support 220 is made of tubular material bent so as to form a rigid open structure. The side frames of said support 220 are connected with each other by a transverse rod 230. The support 220 has an upwardly extending arm 217 on each side of the chair.

The polygonal compound linkage of the chair shown in Fig. 6 substantially corresponds to the polygonal compound linkage of the chair shown in Fig. 1. Again, the back-rest 232 is pivoted to the support 220 at 234 at a point spaced from the pivotal connection 238 between the seat 236 and the support 220. The front link 240 representing an upper extension of the leg-rest 290 is pivoted to the seat 236 at 242. The upper end portion of the front link 240 is pivoted at 244 to the front portion 219 of the top link 246, the rear portion 221 of which is pivoted to the back-rest 232 at 248.

The front portion 219 and the rear portion 221 of the top link 246 are connected with each other

by an intermediate portion 252 in the shape of a guiding rod slidably engaged with the upper portion 256 of the guiding link 258 embracing said guiding rod in the shape of a slider. A bar 266 representing an arm-rest and covering the guiding rod 252 from above is secured to the front portion 219 and the rear portion 221 of the top link 246 by screws 269. As best shown in Figs. 7 and 8, the lower portion of the guiding link 258 is swingably mounted on the pivot 264 secured to the arm 217 of the support 220 at a point spaced from the pivot 234 and 238 between the support 220 and the back-rest 332 and seat 236 respectively. The guiding link 258 is provided with a slot 223 for slidable engagement with a bolt 225 of a locking device generally indicated by 272. The bolt 220 having a head 274 is provided with a square portion 276 inserted into a corresponding square aperture of the arm 217 of the support 220. The square portion 276 prevents the bolt 225 from rotation when a locking knob 278 screwed on the threaded end of the bolt 225 is turned. When the locking knob 278 is loosened, the guiding link 258 and the movable members of the chair connected with said guiding link 258 as described above may freely swing from one position into another one. When the locking knob 278 is tightened, the guiding link 258 and the movable members of the chair connected with said guiding link are firmly held in their positions.

The sitting position of the movable members of the chair shown in full lines in Fig. 6 is limited by the cross bar 230 on which the seat 236 comes to a rest. The extreme reclined position of the movable members of the chair shown in dash and dot lines in Fig. 6 is limited by an abutment of the surface 227 of the front portion 219 of the top link against the slider 256.

The adjustable reclining chair shown in Fig. 9 comprises a support 320 having side walls 327 and 329 connected with each other by cross-bars 328 and 330.

The back-rest 332 is pivoted to the support 320 at 334 at a point spaced from the pivotal connection 338 of the seat 236 with the support 320. A front link 340 rigidly connected with a leg-rest 396 is swingably mounted on the seat 336 at 342. The upper portion of said front link 340 is pivoted to the front portion 319 of the top link 346 at 344. The rear portion 321 of the top link 346 is pivotally connected with an intermediate point of the back-rest 332 at 348. The front portion 319 and the rear portion 321 of the top link 346 are connected with each other by a hollow intermediate portion 350 of said top link. A portion of the inner surface of said hollow portion 350 of the top link 346 forms a guiding means or guiding surface for a slider 356 rigidly connected with the upper end of a guiding link 358, the lower end of which is swingably mounted on the support 320 at 364 at a point spaced from the pivot 334 and 338 between the support 320 and the back-rest 332 and the seat 236 respectively. As may be readily gathered from Figs. 10 and 12, the slider 356 and the upper portion of the guiding link 358 are concealed by the walls of the hollow portion 350 of the top link 346; the guiding link 358 passes through and projects from the slot 362 arranged at the lower portion of the hollow portion 350 of the top link.

When the back-rest 332 is swung about its pivot 334, for example from its upright position shown in full lines in Fig. 9 into the extreme

reclined position shown in dash and dot lines in Fig. 9, the seat 336 and the leg-rest 396 are brought into the position shown in dash and dot lines through the medium of above described 5 polygonal compound linkage.

The sitting position of the movable members of the chair shown in full lines is limited by the cross-bar 330 cooperating with the seat 336, and the extreme reclined position shown in dash 10 and dot lines is limited by an abutment of the slider 356 against the surface 357 of the front portion 319 of the top link 346.

The movable members of the chair may be held in any desired position by means of a locking device generally indicated by 331 and arranged on the pivot 348 connecting the rear portion 321 of the top link 346 with the back-rest 332. As best shown in Figs. 9 and 11, said locking device 331 comprises a handle 333 screwed on the 15 threaded end of the pivot 348. Said pivot 348 has a head 335 resting against the surface of the back-rest 332. A square portion 337 of the pivot 348 is inserted into a corresponding square aperture of the back-rest 332, whereby the pivot 348 is prevented from rotation when the locking lever 333 is turned. When the user of the chair loosens the locking handle 333, the surface of the hub 339 of said handle is disengaged from the surface of the rear portion 321 of the top 20 link 346, so that the movable members of the chair may be freely moved from one position into another one. When the locking handle 333 is tightened, the surface of the hub of the handle is pressed against the rear portion 321 of the top link 346, whereby the latter is pressed against the back-rest 332 engaged with the head 335 of the pivot 348, so that the members of the chair are held in their position. Of course, any other type of locking device may be used instead of 25 said locking device 331, if desired.

According to the embodiment of an adjustable reclining chair shown in Fig. 13, the support 420 comprises the side walls 427 and 429 connected with each other by crossbars 428 and 430.

As best shown in Figs. 14 and 15 a guiding rod 452 arranged within a hollow portion 441 of the top link 446 is secured to the latter by screws 454. A hook-like member 443 is screwed into a 30 threaded bore of the guiding rod 452.

The lower end of the back-rest 432 is pivoted to the support 420 at 434 at a point spaced from the pivotal connection 438 between the seat 436 and the support. The lower end of the front link 440 is pivoted to the front portion of the seat 436 at 442. The upper portion of said front link 440 is swingably mounted on the hook-like member 443 at 445 below the plane of the longitudinal axis of the top link 446. The rear portion of the top link 446 is pivoted to an intermediate point of the back-rest 432 at 448.

Thus, the guiding rod 452 is arranged on an extension 441 of the top link 446 projecting beyond the pivotal connection 445 of the front link 440 with the top link 446.

As best shown in Figs. 14 and 15, the guiding link 458 is in the shape of a clip slidably engaged at its upper end 456 with the guiding rod 452 within the hollow extension 441 of the top link 446. The lower end portion of the clip 458 is swingably mounted on the bolt 464 immovably connected with the side wall 427 of the support 420. A locking knob 478 is screwed on the threaded end of the bolt 464. When the locking knob 478 of the locking device generally indicated by 472 is tightened, the clip 458 is tightened.

on the guiding rod 452 whereby the movable members of the chair are held in their position. When the locking knob 478 is loosened, the guiding rod 452 may freely slide in the clip 458, so that the movable members of the chair may be readily moved from one position into another one.

The sitting position of the movable members of the chair shown in full lines in Fig. 13 is limited by the cross-bar 430 cooperating with the seat 436. The extreme reclined position of the movable members of the chair shown in dash and dot lines in Fig. 13 is limited by an abutment of the portion 456 of the clip 458 against a stop collar 470 secured to the guiding rod 452 as best shown in Fig. 14.

I have described preferred embodiments of my invention but it is understood that this disclosure is for the purpose of illustration, and that various omissions or changes in shape, proportion, and arrangement of parts as well as the substitution of equivalent elements for the arrangement shown and described may be made without departing from the spirit and scope of the invention as set forth in the appended claims.

For example, the guiding rod slidably engaged with the slider mounted on the guiding link must not necessarily be arranged within a hollow portion of the top link; the guiding rod could also be arranged outside the top link proper.

Furthermore, the guiding rod may be omitted entirely, and the slider may embrace a guiding surface on the body of the top link proper.

Moreover, the swingable connection between the lower end of the guiding link and the support may be arranged in coaxial alignment with the swingable connection between the rear portion of the seat and the support, if desired.

Furthermore, the invention may be applied to other articles of furniture than the type of chairs shown in the drawings, for example, to office chairs, chairs for use in railroad cars, chairs for use in airplanes, lounges, etc.

What I claim is:

1. A reclining article of furniture, comprising: a support, a back-rest pivoted to said support, a seat, the rear portion of said seat being pivoted to said support at a point spaced from the pivotal connection between said back-rest and said support, a front link, a top link arranged above the plane of said seat, the lower portion of said front link being pivoted to the front portion of said seat, the upper portion of said front link being pivoted to said top link, the rear portion of said top link being pivoted to an intermediate point of said back-rest, and a guiding link, one end of said guiding link being pivoted to said support at a point spaced from the pivotal connection between the back-rest and the support, and the other end of said guiding link being shiftably engaged with said top link.

2. A reclining article of furniture, comprising: a support, a back-rest pivoted to said support, a seat, the rear portion of said seat being pivoted to said support at a point spaced from the pivotal connection between said back-rest and said support, a front link, a top link arranged above the plane of said seat, the lower portion of said front link being pivoted to the front portion of said seat, the upper portion of said front link being pivoted to said top link, the rear portion of said top link being pivoted to an intermediate point of said back-rest, a guiding link, one end of said guiding link being pivoted to said support

5 at a point spaced from the pivotal connection between the back-rest and the support, and a slidable connection between the other end of said guiding link and said top link.

3. A reclining article of furniture, comprising: a support, a back-rest pivoted to said support, a seat, the rear portion of said seat being pivoted to said support at a point spaced from the pivotal connection between said back-rest and said support, a front link, a top link arranged above the plane of said seat, the lower portion of said front link being pivoted to the front portion of said seat, the upper portion of said front link being pivoted to said top link, the rear portion of said top link being pivoted to an intermediate point of said back-rest, guiding means arranged on said top link, a guiding link, one end of said guiding link being pivoted to said support at a point spaced from the pivotal connection between the back-rest and the support, and a slider mounted on the other end of said guiding link for a slidable engagement with said guiding means.

4. A reclining article of furniture, comprising: a support, a back-rest pivoted to said support, a seat, the rear portion of said seat being pivoted to said support at a point spaced from the pivotal connection between said back-rest and said support, a front link, a top link arranged above the plane of said seat, the lower portion of said front link being pivoted to the front portion of said seat, the upper portion of said front link being pivoted to said top link, the rear portion of said top link being pivoted to an intermediate point of said back-rest, a guiding link, one end of said guiding link being pivoted to said support at a point spaced from the pivotal connection between the back-rest and the support, at least a portion of said top link being hollow and having a slot for the passage of the other end portion of said guiding link, guiding means arranged within said hollow portion of the top link, and a slider mounted on said other end of the guiding link for a slidable engagement with said guiding means arranged within the hollow portion of the top link.

5. A reclining article of furniture, comprising: a support, a back-rest pivoted to said support, a seat, the rear portion of said seat being pivoted to said support at a point spaced from the pivotal connection between said back-rest and said support, a front link, a top link arranged above the plane of said seat, the lower portion of said front link being pivoted to the front portion of said seat, the upper portion of said front link being pivoted to said top link, the rear portion of said top link being pivoted to an intermediate point of said back-rest, a guiding rod mounted on said top link, a guiding link, one end of said guiding link being pivoted to said support at a point spaced from the pivotal connection between the back-rest and the support, and a slider mounted on the other end of said guiding link and slidably engaged with said guiding rod mounted on the top link.

6. A reclining article of furniture, comprising: a support, a back-rest pivoted to said support, a seat, the rear portion of said seat being pivoted to said support at a point spaced from the pivotal connection between said back-rest and said support, a front link, a top link arranged above the plane of said seat, the lower portion of said front link being pivoted to the front portion of said seat, the upper portion of said front link being pivoted to said top link, the

rear portion of said top link being pivoted to an intermediate point of said back-rest, a guiding link, one end of said guiding link being pivoted to said support at a point spaced from the pivotal connection between the back-rest and the support, at least a portion of said top link being hollow and having a slot for the passage of the other end portion of said guiding link, a guiding rod arranged within said hollow portion of the top link, and a slider mounted on said other end of the guiding link and slidably engaged with said guiding rod arranged within the hollow portion of the top link.

7. A reclining article of furniture, comprising: a support, a back-rest pivoted to said support, a seat, the rear portion of said seat being pivoted to said support at a point spaced from the pivotal connection between said back-rest and said support, a front link, a top link arranged above the plane of said seat, the lower portion of said front link being pivoted to the front portion of said seat, the upper portion of said front link being pivoted to said top link, the rear portion of said top link being pivoted to an intermediate point of said back-rest, a guiding surface on said top link, a guiding link, one end of said guiding link being pivoted to said support, and a slider mounted on the other end of said guiding link for slidable engagement with said guiding surface of the top link.

8. A reclining article of furniture, comprising: a support, a back-rest pivoted to said support, a seat, the rear portion of said seat being pivoted to said support at a point spaced from the pivotal connection between said back-rest and said support, a front link, a top link arranged above the plane of said seat, the lower portion of said front link being pivoted to the front portion of said seat, the upper portion of said front link being pivoted to said top link, the rear portion of said top link being pivoted to an intermediate point of said back-rest, a guiding link, one end of said guiding link being pivoted to said support at a point spaced from the pivotal connection between the back-rest and the support, at least a portion of said top link being hollow and having a slot for the passage of the other end portion of said guiding link, the inner surface of said hollow portion of the top link including a guiding surface, and a slider mounted on said other end of the guiding link for slidable engagement with said guiding surface of the hollow portion of the top link.

9. A reclining article of furniture, comprising: a support, a back-rest pivoted to said support, a seat, the rear portion of said seat being pivoted to said support at a point spaced from the pivotal connection between said back-rest and said support, a front link, a top link arranged above the plane of said seat, the lower portion of said front link being pivoted to the front portion of said seat, the upper portion of said front link being pivoted to said top link, the rear portion of said top link being pivoted to an intermediate point of said back-rest, a guiding link, one end of said guiding link being pivoted to said support at a point spaced from the pivotal connection between the back-rest and the support, a slideable connection between the other end of said guiding link and said top link, and locking means associated with said guiding link and the support for locking the movable members of the article in a predetermined position.

10. A reclining article of furniture, comprising: a support, a back-rest pivoted to said support,

a seat, the rear portion of said seat being pivoted to said support at a point spaced from the pivotal connection between said back-rest and said support, a front link, a top link arranged above the plane of said seat, the lower portion of said front link being pivoted to the front portion of said seat, the upper portion of said front link being pivoted to said top link, the rear portion of said top link being pivoted to an intermediate point

5 of said back-rest, guiding means arranged on said top link, a clip, one end of said clip being pivoted to said support at a point spaced from the pivotal connection between the back-rest and the support, the other end of said clip being slidably engaged with said guiding means arranged on the top link, and locking means associated with said clip for tightening same on said guiding means so as to lock the movable members of the article in a predetermined position.

10. 11. A reclining article of furniture, comprising: a support, a back-rest pivoted to said support, a seat, the rear portion of said seat being pivoted to said support at a point spaced from the pivotal connection between said back-rest and said support,

15 a front link, a top link arranged above the plane of said seat, the lower portion of said front link being pivoted to the front portion of said seat, the upper portion of said front link being pivoted to said top link, the rear portion of said

20 top link being pivoted to an intermediate point of said back-rest, guiding means arranged on said top link, a guiding link, one end of said guiding link being pivoted to said support at a point spaced from the pivotal connection between

25 the back-rest and the support, a slider mounted on the other end of said guiding link for a slideable engagement with said guiding means arranged on the top link, and a stop mounted on said top link for cooperation with said slider so as to limit the extreme reclined position of the

30 movable members of the article.

35 12. A reclining article of furniture, comprising: a support, a back-rest pivoted to said support, a seat, the rear portion of said seat being pivoted to said support at a point spaced from the pivotal connection between said back-rest and said support,

40 a front link, a top link arranged above the plane of said seat, the lower portion of said front link being pivoted to the front portion of said seat, the upper portion of said front link being pivoted to said top link, the rear portion of said

45 top link being pivoted to an intermediate point of said back-rest, a guiding link, one end of said guiding link being pivoted to said support at a point spaced from the pivotal connection between the back-rest and the support, the other end of said guiding link being shiftably engaged with said top link, and a spring catch mounted on said top link for cooperation with said shift-

50 able connection between the guiding link and the top link so as to hold the guiding link in a predetermined position relative to the top link.

55 13. A reclining article of furniture, comprising: a support, a back-rest pivoted to said support, a seat, the rear portion of said seat being pivoted to said support at a point spaced from the pivotal connection between said back-rest and said support,

60 a front link, a top link arranged above the plane of said seat, the lower portion of said front link being pivoted to the front portion of said seat, the upper portion of said front link being pivoted to said top link, the rear portion of said

65 top link being pivoted to an intermediate point of said back-rest, and a guiding link, one end of said guiding link being pivoted to said support at a point spaced from the pivotal connection between the back-rest and the support, the other end of said guiding link being shiftably engaged with said top link, and a spring catch mounted on said top link for cooperation with said shift-

70 able connection between the guiding link and the top link so as to hold the guiding link in a predetermined position relative to the top link.

75 14. A reclining article of furniture, comprising: a support, a back-rest pivoted to said support, a seat, the rear portion of said seat being pivoted to said support at a point spaced from the pivotal connection between said back-rest and said support,

80 a front link, a top link arranged above the plane of said seat, the lower portion of said front link being pivoted to the front portion of said seat, the upper portion of said front link being pivoted to said top link, the rear portion of said

85 top link being pivoted to an intermediate point of said back-rest, and a guiding link, one end of said guiding link being pivoted to said support at a point spaced from the pivotal connection between the back-rest and the support, the other end of said guiding link being shiftably engaged with said top link, and a spring catch mounted on said top link for cooperation with said shift-

11

support at a point spaced from the pivotal connection between the back-rest and the support, and the other end of said guiding link being shiftably engaged with an intermediate portion of said top link between its pivotal connections with the front link and the back-rest.

14. A reclining article of furniture, comprising: a support, a back-rest pivoted to said support, a seat, the rear portion of said seat being pivoted to said support at a point spaced from the pivotal connection between said back-rest and said support, a front link, a top link arranged above the plane of said seat, the lower portion of said front link being pivoted to the front portion of said seat, the upper portion of said front link being pivoted to said top link, the rear portion of said top link being pivoted to an intermediate point of said back-rest, said top link having a forward extension projecting beyond its pivotal connection with the front link, and a guiding link, one end of said guiding link being pivoted to said support at a point spaced from the pivotal connection between the back-rest and the support, and the other end of said guiding link being shiftably engaged with said forward extension of the top link.

15. A reclining article of furniture, comprising: a support, a back-rest pivoted to said support, a seat, the rear portion of said seat being pivoted to said support at a point spaced from the pivotal connection between said back-rest and said support, a front link, a top link arranged above the plane of said seat, the lower portion of said front link being pivoted to the front portion of said seat, the upper portion of said front link being pivoted to said top link, the rear portion of said top link being pivoted to an intermediate point of said back-rest, and a guiding link, one end of said guiding link being pivoted to said support at a point spaced from the pivotal connection between the back-rest and the support, and spaced from the pivotal connection between the seat and the support, and the other end of said guiding link being shiftably connected with said top link.

12

16. A reclining article of furniture, comprising: a support, a back-rest pivoted to said support, a seat, the rear portion of said seat being pivoted to said support at a point spaced from the pivotal connection between said back-rest and said support, a front link, a top link arranged above the plane of said seat, the lower portion of said front link being pivoted to the front portion of said seat, the upper portion of said front link being pivoted to said top link, the rear portion of said top link being pivoted to an intermediate point of said back-rest, a guiding link, one end of said guiding link being pivoted to said support at a point spaced from the pivotal connection between the back-rest and the support, the other end of said guiding link being shiftably engaged with said top link, a leg-rest swingably mounted on the front portion of the seat, and means for controlling the movements of the leg-rest in dependence on movements of a movable member of the article.
